United States Patent

Des. 236,477
Patented Aug. 26, 1975

236,477

METAL FORM UNIT

Carl H. Niendorf, Des Moines, Iowa, assignor to Economy Forms Corporation

Filed May 30, 1974, Ser. No. 474,696

Term of patent 14 years

Int. Cl. D25—99

U.S. Cl. D13—1 H

FIG. 1 is a perspective view looking toward the front side of a metal form unit of my new design;

FIG. 2 is a top view;

FIG. 3 is an end view;

FIG. 4 is a rear side view;

FIG. 5 is a front side view; and

FIG. 6 is a bottom view.

I claim:

The ornamental design for a metal form unit, substantially as shown.
